Primary Examiner — Philip S Hyder*Assistant Examiner* — Darlington Ly(74) *Attorney, Agent, or Firm* — Greenberg Traurig, LLP(57) **CLAIM**

What is claimed is the ornamental design for an auto hammer, as shown and described.

DESCRIPTION

FIG. 1 is a left side elevational view of an auto hammer showing my new design;

FIG. 2 is a right side elevational view thereof;

FIG. 3 is a front elevational view thereof;

FIG. 4 is a rear elevational view thereof;

FIG. 5 is a top plan view thereof; and,

FIG. 6 is a perspective view thereof.

The broken lines shown in the drawings illustrate portions of the auto hammer that forms no part of claimed design.
